UNITED STATES PATENT OFFICE

105,513

DESIGN FOR A COMMUNICATIONS UNIT CABINET

Stuart J. Cardoza, Berkeley, Calif., assignor to
Lake Manufacturing Company, Oakland, Calif.,
a corporation of California

Application May 17, 1937, Serial No. 69,393

Term of patent 7 years

To all whom it may concern:

Be it known that I, Stuart J. Cardoza, a citizen of the United States, residing at Berkeley, in the county of Alameda and State of California, have invented a new, original, and ornamental Design for a Communications Unit Cabinet, of which the following is a specification, reference being had to the accompanying drawing, forming part thereof.

Fig. 1 is a perspective view of the communications unit cabinet showing my new design;

Fig. 2 is a top plan view; and
Fig. 3 is a side elevational view.
Both sides of the cabinet are like that shown in Fig. 3. The bottom portion, or rear portion, depending upon its placement in use, is open and adapted to receive any type or form of communications unit.

I claim:

The ornamental design for a communications unit cabinet substantially as shown and described.

STUART J. CARDOZA.
